HIS ATTORNEY,

UNITED STATES PATENT OFFICE.

FRANK HOLDEN, OF LONDON, ENGLAND, ASSIGNOR TO GENERAL ELECTRIC COMPANY,
A CORPORATION OF NEW YORK.

ELECTRIC CLOCK.

1,111,383.

Specification of Letters Patent. Patented Sept. 22, 1914.

Application filed November 30, 1912. Serial No. 734,293.

To all whom it may concern:

Be it known that I, FRANK HOLDEN, a citizen of the United States, residing at London, England, have invented certain new and useful Improvements in Electric Clocks, of which the following is a specification.

This invention relates to electric clocks, and more particularly to clocks of the type in which the indicating mechanism is driven by a pendulum or balance wheel which periodically receives an impulse by the completion of an electric circuit controlled by a contact carried by the pendulum.

15 The object of this invention is to relieve the pendulum of the work of driving the mechanism, thereby reducing the friction which normally acts to vary the time of the pendulum or balance wheel in this type of 20 clock.

To this end the invention consists in the employment of an auxiliary driving device, such as a small motor for operating the mechanism, the circuit of the motor being 25 supplied with current from a battery or other convenient source and controlled by a contact carried by the pendulum.

In the accompanying drawing, Figure 1 illustrates diagrammatically one form of the 30 invention, Fig. 2 is a diagrammatic view of certain of the electrical connections, and Fig. 3 illustrates a modified detail of construction.

Referring to the figures of the drawing, 35 there is shown a pendulum 1 which is similar to that described in British Patent, No. 14,873 of 1909. The pendulum carries a coil 2 adapted to swing in the magnetic field of the permanent magnets 16 and periodically energized to produce an impulse by means of a pivoted contact 3. The contact 3 is also carried by the pendulum and is adapted to engage the fixed contacts 4, thus completing an electric circuit. Fig. 2 of the 45 drawings illustrates diagrammatically the electrical connections of the circuit.

Instead of utilizing the movement of the pendulum for operating directly the indicating or clock mechanism, I provide an efficient electric motor 5 having small internal losses, such as is used in some types of electric meters. This motor is connected in any suitable manner, as for example, by means of a chain or cord 6, to a wheel 7 provided

with one or more radially projecting pins 8 or contacts 8, preferably of some good conducting material, such as silver.

The wheel 7 is rotatably mounted in such a position that the pin or pins 8 project into the path of a flexible contact 9 carried by the pendulum. The motor is supplied with current from a convenient source, such as a battery 10, which may be the same as that supplying the current for actuating the pendulum, or may be a separate battery. One terminal of this battery is connected to the pendulum, while the other is connected through the motor armature to the clock mechanism or contact wheel in such a manner that the circuit is completed when one of the pins 8 on the wheel is engaged by the flexible contact 9 on the pendulum. The contact wheel is connected to the indicating or clock mechanism, which comprises the gearing 11 and the indicating hands 12, so that the motor when supplied with current drives said mechanism through the contact wheel.

The operation is as follows: When the pendulum is swinging in one direction, for example from left to right in the drawing, the flexible contact 9 carried thereby engages one of the pins 8 on the contact wheel. This completes the circuit of the motor which immediately accelerates, driving the contact wheel and the clock mechanism through the chain or cord 6. On the return stroke the flexible contact does not engage a contact on the wheel 7, as these contacts are preferably so arranged as not to come into the path of the flexible contact on the return stroke. If not so arranged, however, the flexible contact may be hinged, as shown at 14 in Fig. 3, so as to ride freely over the wheel contacts on the return stroke, in which case the back of the flexible contact or the portion of the wheel contacts engaged thereby may be insulated as at 15, so that the motor circuit will not be completed.

The moment of inertia of the motor is such that when once started it will run for a considerable time at a practically constant speed and during this time its circuit may or may not be completed through the moving contacts. The electrical characteristics of the motor are such that, without the operation of the pendulum, it runs a few per cent. slow, or as nearly as practicable to, but

always less than, the speed required to make the clock give the right time. Thus, granted a starting condition under which the pendulum and revolving contacts synchronize, it is evident that the revolving contacts cannot gain appreciably on the pendulum contact, as the contacts no longer close the motor circuit, and the motor loses the accelerating effect of the applied voltage. It is a matter of proportioning the electrical characteristics of the motor to arrange that the closing of the contacts produces enough acceleration so that the revolving contacts cannot fall behind the pendulum contact. Thus before an appreciable decrease in speed of the revolving contacts takes place a contact on the contact wheel engages the pendulum contact to complete the motor circuit and accelerate the motor. These accelerating impulses will occur at substantially regular intervals so that the number of revolutions made by the contact wheel in equal intervals of time will be absolutely constant, and the hands of the clock will therefore be moved through equal angles. The pendulum thus acts to maintain the speed of the motor constant and may be regarded as a means for synchronizing the motor.

With a driving mechanism, such as above described, the movement of the hands, the second hand more particularly, is continuous and not periodic as is the case with the usual pendulum driven clocks.

It will be obvious that various modifications of the arrangement described above, may be made without departing from the spirit and scope of this invention.

What I claim as new and desire to secure by Letters Patent of the United States, is:

1. An electric clock comprising an electric motor having a continuously rotatable member, an electric circuit operatively re-

lated to said motor, and a pendulum adapted to control said circuit.

2. An electric clock comprising a clock mechanism, an electric motor having a continuously rotatable member operatively connected to said mechanism, an electric circuit operatively related to said motor, a movable contact included in said circuit and adapted to be actuated by said motor, a second movable contact included in said circuit and cooperating with said first mentioned movable contact, and a pendulum adapted to actuate said second movable contact. 55

3. An electric clock comprising an indicating mechanism, an electric motor operatively connected to said mechanism, an electric circuit in operative relation to said motor, and a pendulum adapted to complete 60 said circuit when the speed of the motor decreases a predetermined amount.

4. An electric clock comprising an indicating mechanism, an electric motor having a continuously rotatable member for driving 65 said mechanism, an electric circuit operatively related to said motor, and a pendulum adapted to control said circuit.

5. An electric clock comprising an indicating mechanism, an electric motor for 70 driving said mechanism, an electric circuit in operative relation to said motor, a contact wheel in said circuit and driven by said motor, and a pendulum having a contact included in said electric circuit and adapted 75 to engage said contact wheel when the speed of the motor decreases a predetermined amount.

In witness whereof, I have hereunto set my hand this 13th day of November, 1912. 80

FRANK HOLDEN.
